HYDROCARBON DETECTION

Pernell J. Moore, Houston, Tex., assignor to National Lead Company, New York, N.Y., a corporation of New Jersey

Application May 4, 1956, Serial No. 582,823

4 Claims. (Cl. 23—232)

This invention relates to the selective detection and estimation of hydrocarbons and more particularly to an improvement in hydrocarbon detectors of the catalytic filament type.

It has been known for many years that certain metals, particularly platinum, have the ability when suitably heated to maintain catalytic combustion at the metal surface of relatively small amounts of combustible gases such as hydrocarbons when present in air, at temperatures below that corresponding to the self-ignition temperature for the same mixtures in the absence of catalytic agencies. This property has been made use of in the so-called hot-wire filament gas detector, examples of which may be found described in the literature and in numerous patents, such as United States Patent No. 524,361 to Tilghman and United States Patent No. 1,562,243 to Moeller.

In the operation of such detectors, it has likewise been known that methane requires a higher filament temperature for combustion than do higher hydrocarbons, such as ethane, propane, butane, pentane, and indeed hydrocarbons generally having more than one carbon atom per molecule. Where hot-wire gas detectors are used in the testing of cuttings and mud returns during the course of drilling a well for oil or gas, in order to determine if a gas or oil-bearing zone has been struck, use has been made of this anomalous property of methane by making a determination at two different filament temperatures, effected by the use of two different filament voltages, one voltage high enough to combust all of the hydrocarbons present, and the other temperature somewhat lower so that all of the hydrocarbons save methane are combusted. A description of this technique is given, for example, in the article by B. Otto Pixler appearing in the May 1946 issue of Petroleum Technology.

Now there are advantages in selectively detecting those higher hydrocarbons which may be present, particularly in prospecting and exploration activities connected with drilling for petroleum. Indications of some importance as to the nature of the petroleum deposit in question may be given by knowing the relative proportions of the several higher hydrocarbons present, or at least groups thereof. Indeed, it has been standard practice, where a formation encountered during drilling is subjected to sampling by means of a so-called formation tester, to take a sample of the liquid and gaseous hydrocarbons obtained to an analytical laboratory and determine the hydrocarbon composition thereof.

It would obviously be to a considerable advantage if at least an approximate idea of the distribution of the higher hydrocarbon group could be obtained in the field and more or less instantaneously by the means of a simple device such as the hot-wire gas detector. The advantage of such a result has been prevented in the past, however, by the fact that as the temperature of a filament, for example, of platinum, is progressively raised, all of the hydrocarbons of molecular weight higher than methane combust as a group. Thus, differentiation has been

2

limited to methane, on the one hand, and all higher hydrocarbons on the other.

An object of the invention is to provide an apparatus and process for the differential detection of hydrocarbons, particularly those in a normally gaseous state or the more volatile liquid hydrocarbons.

Another object of the invention is to provide an apparatus and process for the estimation of the relative amounts of gaseous hydrocarbons in admixture with air.

10 Another object of the invention is to provide a method for differentiating between hydrocarbons higher in carbon chain length than pentane, and those lower.

Another object of the invention is to provide a method of hydrocarbon detection of great usefulness in petroleum prospecting and drilling.

Other objects of the invention will become apparent as the description thereof proceeds.

In the drawings,

Fig. 1 is a view of an apparatus which can be used for carrying out the principal objects of the invention.

Fig. 2 is a wiring diagram showing the electrical connections for a suitable circuit including the apparatus of Fig. 1.

Fig. 3 is a graph showing the response of a pure platinum filament, and also the response of a platinum-rhodium alloy filament to various hydrocarbons.

Fig. 4 is a graph showing the response of a platinum-copper alloy filament to various hydrocarbons.

Fig. 5 is a graph showing the response of a platinum filament bearing a thin copper plating in accordance with the invention, to various hydrocarbons.

I have discovered that if, in a heated-filament gas detector of the general type which has been described, the surface of the catalytic wire of platinum or palladium has been caused to become impure, and the definite steps are followed of maintaining such a filament at a highly elevated temperature of about 700-800° C., or even higher (but naturally not to the melting point of the metal) for a few seconds and then lowering the filament temperature to the unusually low temperature of about 300° C., then for a period of time which lasts generally from at least half a minute and occasionally for several minutes, the filament exhibits selectively as regards the several hydrocarbons higher than methane, and moreover, in such a way that the hydrocarbons of high molecular weight will combust and therefore may be detected at relatively low filament temperatures, approximately 300° C., but the response of progressively lighter hydrocarbons is delayed to higher temperatures, but not as high as would be the case if the filament had not undergone the treatment just described.

The most convenient way of carrying out the differential detection following the treatment as described is, with the filament at the lower temperature of about 300° C. following its flash heating to the higher temperature described, to raise the filament temperature slowly, which is conveniently accomplished by raising the voltage across the filament, and then registering the response of the filament as the hydrocarbons which may be present are successively combusted in the approximate inverse order of molecular weights, care being taken to accomplish the whole temperature-raising process within the time limit set by the duration of the peculiar selective property of the filament, which in a practical way, is from half a minute to three or four minutes.

65 The response of the filament to combustion is generally and most conveniently determined by an electrical circuit designed to respond to fluctuations in the electrical resistance of the filament, since the catalytic metals used, particularly platinum, have high temperature coefficients of electrical resistance and combustion at their surface naturally raises the temperature of the filament somewhat.

and accordingly their resistance. A convenient and simple electrical circuit will be described below, in connection with Fig. 2 of the drawings. However, the method of detecting combustion may be accomplished by other means, among which may be the pyrometric observation of the temperature of the filament, and again, the attaching of a thermocouple to the filament at a convenient point, so that a thermoelectric response is obtained when the temperature of the filament rises in response to surface combustion. All of these may be termed means for registering the temperature of the wire or filament.

I have found, in general, that there are two ways of making the surface of the filament impure so that when the process described is carried out, hydrocarbon selectivity is the result. But it is to be understood that I do not mean to be limited to these two general ways of bringing about an impure surface state of the filament, which generally will be of a platinum or palladium base.

The first general method is to coat the filament, which may be platinum or palladium, or others of the platinum group, with a very thin coating of an adherent metal which does not have too high a vapor pressure at 800° C. and is compatible with platinum from an alloying standpoint. Nickel, silver and gold plating have been found to be effective. Copper is also suitable, and all of these may be applied as a coating by electrodeposition. Platinum group metals other than platinum or palladium are also available, such as iridium, rhodium, and ruthenium. These and other suitable metals may also be applied by chemical deposition as used, for example, in the mirror silvering art; or by dipping in the molten metal followed by etching chemically to the desired coating thickness; by sputtering in a vacuum; and by other methods which will give an adherent coating of the desired thinness, preferably between 0.00005 and 0.0005 inch. All of these coating or allowing metals may be termed "heavy metals." Heavy metals other than platinum and palladium are used.

I am aware that coating of platinum filaments has been practiced in this particular art, but such coating, generally of gold, is ordinarily carried out to inactivate a filament completely so that it can be used as a compensator filament in a Wheatstone bridge circuit while still being exposed to the combustible vapors. My coating, on the other hand, is much thinner than a deactivating coating, and merely gives a slight contamination of the surface of the catalytic metal, so that its catalytic activity is altered without being destroyed. Moreover, my coating process is used in connection with the particular steps which have been described, which consist of raising the filament to a surface temperature in a relatively high range, lowering it to a relatively low range, and then making the desired detections which may be carried out by gradually increasing the surface temperature of the contaminated filament.

A second general method of achieving a suitably impure filament surface is to form the filament of an alloy itself so that the filament contains a foreign metal. I have discovered that such alloys as 5% iridium and 95% platinum; 10% rhodium and 90% platinum; 20% rhodium and 80% platinum, are typical of the alloys which will operate in the manner described when subjected to the process described in yielding selective action. In general, when such an alloy is used, it should consist of about 80 to 95% of the catalytic metal, such as platinum, and the balance the foreign metal chosen. In general, a smaller rather than a larger proportion of the foreign metal is preferable, since its presence tends to reduce the temperature coefficient of resistivity of the pure metal, viz., platinum. About a 95:5 alloy is thus preferable in the general case. Here again, I am aware that such alloys, particularly of metals within the platinum group, have been used, particularly in the hot-wire gas detectors in both the compensating and detector structures, but here the purpose was to obtain

greater mechanical strength. Such filaments have not been used in the fashion described by me, that is, in connection with the process which has been described, which results, even though for a relatively short period of time, in the phenomenon of differential selectivity of the catalytic surface.

Coming now to Figure 1, this shows a mechanical arrangement which I have found to be suitable. In the figure, 10 indicates a metal sleeve into which is fitted 10 a base 11, which should be of insulating material and for which a thermosetting plastic, such as Bakelite is suitable, and into which in turn is embedded a support rod 12, conveniently made of brass. Two shorter support rods 13 are likewise embedded in the base 11, and these 15 three support rods are electrically connected with a three-wire cable 14, of which a portion is shown in the figure. Toward the end of support rod 12, a stirrup 15 is attached, as by soldering. This stirrup may likewise be conveniently made of brass, and furnishes a means 20 for suspending two filaments 16 and 17 in spaced relationship to support 13. Of the two filaments, 16 is the detector filament and is prepared for differential selectivity as has been described. In this illustrative embodiment, filament 16 may be a one and one-half inch length 25 of a 90:10 platinum:rhodium alloy wire which is 0.004" in diameter. Filament 17 is a filament designed to have similar electrical and mechanical properties, except that it lacks catalytic activity altogether. In this illustrative embodiment, filament 17 may consist of a one and one-half inch length of the same platinum-rhodium alloy. It need not be especially inactivated, since as long as it is not flashed at a high temperature as has been described, it will not respond at all at 300° C. If it is desired, however, to detect propane, ethane and methane 30 with the same apparatus, filament 17 may be coated with a thin but complete gold plating. This will cause some mis-match in the filaments as the voltage is raised, which will give a substantial zero shift which however may be cancelled out as described below. A cover 18 is provided which slips over the base 11, and has the major 35 part of its cylindrical portion of a fine wire mesh. For clarity of illustration, cover 18 is shown removed from the filament assembly, but it will be understood that in actual use the protective cover 18 is fitted upon the filament assembly as suggested by the dotted lines in the figure. When thus assembled, the fine wire mesh of the cover 18 permits diffusion and moderate convection of air therethrough, so that the filaments 16 and 17 will 40 be exposed to whatever atmosphere the assembly as a whole is in contact with, and yet the mesh prevents the disturbing action of strong drafts. A hole 19 in the end of the protective cover aids in slow convection when the filament assembly is used in a vertical position as distinguished from a horizontal position.

55

55

Fig. 2 shows a suitable wiring diagram for connecting the filament assembly of Fig. 1 into an operative electrical circuit. In Fig. 2, 16 and 17 denote the two filaments which have been described in connection with Fig. 1, and 60 20 and 21 are two resistances, which may be of 10 ohms each, which are connected through a potentiometer 22, conveniently of 2 ohms resistance, and thus form the other two arms of a Wheatstone bridge circuit. This bridge circuit is energized by the application of a voltage 65 which will be described below. Any unbalance in the bridge is shown by a milliammeter 23, placed across the bridge, and the voltage across the detector filament 16 is indicated by a voltmeter 24. Suitable types are an ordinary D.C. milliammeter of 0-1 millampere range, and a 1000-2000 ohms per volt D.C. voltmeter with a scale range of 0-5 volts, respectively. A source of direct current 70 for energizing the bridge circuit is provided, which is most conveniently a 4.5 volt battery 25. For the purpose of switching from an "off" to a "detecting" and also to a "flashing" position, a single-pole three-way switch 75 26 is provided. Variable resistors 27 and 28, conven-

tently of 3 ohms and 10 ohms respectively are provided for adjusting the current under the two conditions of "flashing" and "detecting" respectively.

The operation of the selective detector unit is as follows. It will be understood that the filament assembly of Fig. 1 is placed in some location where it is desired to detect selectively the presence of hydrocarbons in the gaseous state. Such a place may be, for example, the upper part of a glass jar in which well-cuttings have been standing for some time; or the upper portion of the jar of a melted milk mixer of the food-homogenizer type where some cuttings or cores recovered during well drilling operations have been churned up with a small amount of water or drilling mud; or it might be the flow line of a drilling oil well just above the level of the issuing mud; or it might be the gases recovered from a gas trap of conventional design, as used in the art, or in particular a gas trap as described in the Wilson et al. Patent No. 2,341,169. Again, it might be placed in the exhaust line of an internal combustion engine, or in the stack of an industrial plant, or the like. Accordingly, with the filament assembly of Fig. 1 placed where it is exposed to the gases wherein hydrocarbons are desired to be detected, the switch 26 is turned to its third or "flashing" position, so that current flows through variable resistor 27 and detector filament 16. Resistor 27 should be adjusted to give a filament temperature of about 700 to 800° C. on filament 16, which may be recognized by a medium-dark red to medium red color. The filament is maintained at this temperature for a few seconds, such as 5 seconds, whereupon the switch is moved to its middle or "detecting" position, the resistor 28 having been previously adjusted by trial so that a filament temperature of not more than 300° C. results. The position of the slide on resistor 28 is gradually moved to a position of lower resistance, so that the temperature of the filaments 16 and 17 increases. The reaction of the meter 23 is noted or registered as a function of the position of resistor 28, which it will be understood can be calibrated in terms of approximate filament temperature if desired. Naturally, before undertaking such a process of detection, the balancing resistor 22 will have been adjusted so that the bridge will be balanced with no hydrocarbon gases being present. It has been found that a single adjustment of balancing resistor 22 gives sufficiently good balance over the range of operating filament temperatures used in detecting the several hydrocarbons from kerosene or heavy crude oil fractions down to ethane. Another switch 29 is shown, which is connected in tandem with switch 26, and serves to protect the meters from damage when the high "flashing" voltage is applied.

Fig. 3 shows some results obtained in subjecting various selective hydrocarbons to detection with and without the use of the improvements of this invention. For the results shown, an apparatus corresponding to that of Figs. 1 and 2 was used where the improvement of the invention was utilized, and the detecting filament 16, was a platinum-rhodium wire, of 0.004" diameter, of 90% platinum and 10% rhodium.

In Fig. 3, the abscissae show the voltage of the filament in question, while the ordinates give the meter reading as obtained in the apparatus shown in Fig. 2. The family of curves at the left labeled "0.004" C.P. Pt." shows the response of an ordinary platinum hot wire to higher hydrocarbons. Curves are shown for butane, pentane, hexane, octane and nonane. The family of curves on the left shows that as the filament voltage is raised to slightly in excess of 0.6 volts, all of these hydrocarbons combust as a group, and it is impractical and indeed impossible to differentiate among them. On the other hand, the family of curves at the right, labeled "0.004" 10% Rh 90% Pt" shows the response obtained when the platinum-rhodium alloy filament described is used. Since the temperature coefficient of resistance is lower than for pure platinum, the meter readings are all low-

er, but this does not prevent a clear distinction to be made between pentane and lower hydrocarbons and butane and higher hydrocarbons. Thus, from Fig. 3 it is seen that when the voltage is raised to about 1.0 volt, 5 octane and nonane are oxidized, and if the filament temperature is progressively raised to about 1.6 to 1.8 volts, hexane pentane and butane are oxidized in a fashion making a clear distinction between them possible.

Fig. 4 shows the invention carried out by means of a 10 platinum-copper alloy filament having the composition of 98% platinum and 2% copper. The diameter of the wire was 0.004". It will be seen from the graph that if the filament voltage is raised to slightly in excess of 1.0 volt, the hydrocarbons from hexane and above are 15 combusted, while it is necessary to increase the voltage in excess of 2.5 volts before pentane and butane are combusted or oxidized. Here again excellent differentiation may be obtained between these two groups of hydrocarbons.

20 Fig. 5 shows the invention as carried out with a filament consisting of pure platinum but bearing a thin coating of copper as has been described. The copper plating was a few ten-thousandths of an inch in thickness, and while it varied somewhat on the filament it was between 25 0.0001" and 0.0005" thick. Here again, it will be seen that when the filament voltage was raised to approximately 0.7 volts, not only nonane but also 35° A.P.I. gravity crude oil combusted. On the other hand it was necessary to raise the filament voltage to in excess of 1.5 volts before pentane and butane were combusted. Excellent differentiation between the group of pentane and lower hydrocarbons and a group of higher hydrocarbons was obtained.

25 It will be observed that the invention accomplishes its 30 objects, and that results which are not only new but of considerable commercial importance are obtainable. It is to be understood, therefore, that the invention is a broad one and although specific embodiments have been described, such modifications as may be made within the 35 broad scope of the invention and appended claims are 40 intended to be included herein.

I claim:

1. In the testing of a plurality of gas samples for hydrocarbon content by a method involving catalytic combustion at the surface of a hot wire, the steps for each 45 sample comprising, first activating by electrically resistance heating a temperature calibrated wire of a first metal chosen from the group consisting of platinum and palladium and alloyed with a minor amount of a second metal compatible with said first metal and chosen from the group consisting of rhodium, iridium, ruthenium, nickel, silver, gold and copper to a temperature of at 50 least 700° C. but below the melting point of the wire for a few seconds, immediately lowering the temperature of 55 the wire to about 300° C., passing said gas into contact with the wire at said lower temperature, maintaining said contact while progressively increasing and noting the wire temperatures, ascertaining the temperatures of the wire and noting excesses in the wire temperature above 60 that resulting solely from the electrical heating to determine the presence of catalytic combustion at various temperatures indicative of the presence of known components of hydrocarbon gases, the higher molecular weight hydrocarbon components of said gas beginning 65 to combust at temperatures not substantially higher than 300° C.

2. In the successive testing of gas samples for component hydrocarbon gases by a method involving catalytic combustion at the surface of a hot wire, the steps 70 for each sample comprising, first activating by electrically resistance heating a temperature calibrated wire of a first metal chosen from a group consisting of platinum and palladium, presenting a surface containing a minor amount of a second metal impurity compatible with said 75 first metal from an alloying standpoint and having a

relatively low pressure at a temperature of the order of 800° C. to a temperature of at least 700° C. but below the melting point of the wire for a few seconds, immediately lowering the temperature of the wire to about 300° C., passing said sample into contact with the wire at said lower temperature, maintaining the contact not longer than the duration of activity of the wire while progressively increasing and noting the calibrated wire temperatures, ascertaining the wire temperatures by known means and noting deviation in the wire temperature above the calibrated temperature to determine the presence of catalytic combustion at various calibrated temperatures below those necessary for combustion without the wire pretreatment and indicative of the presence of known components of hydrocarbon gases.

3. In the successive testing of gas samples for component hydrocarbon gases by a method involving catalytic combustion at the surface of a hot wire, the steps for each sample comprising, first activating by electrically resistance heating a temperature calibrated wire of a first metal chosen from a group consisting of platinum and palladium and alloyed with a minor amount of a second metal impurity compatible with said first metal from an alloying standpoint and having a relatively low vapor pressure at a temperature of the order of 800° C. to a temperature of at least 700° C. but below the melting point of the wire for a few seconds, immediately lowering the temperature of the wire to about 300° C., passing said sample into contact with the wire at said lower temperature, maintaining the contact not longer than the duration of activity of the wire while progressively increasing and noting the calibrated wire temperatures, ascertaining the wire temperatures by known means and noting deviation in the wire temperature above the calibrated temperature to determine the presence of catalytic combustion at various calibrated temperatures in-

dicative of the presence of known components of hydrocarbon gases.

4. A method of testing a plurality of gas samples for hydrocarbon components by catalytic combustion at the surface of a hot wire, comprising the steps for each sample of first activating by electrically resistance heating for a few second without melting a temperature calibrated wire to a temperature of at least 700° C., said wire composed of the order of 95% of a metal from the group consisting of platinum and palladium and of the order of 5% of a metal compatible with said metal from an alloying standpoint and from the group having a relatively low vapor pressure at a temperature of the order of 800° C., immediately lowering the wire temperature to the order of 300° C., immediately contacting said wire and gas sample and detecting, if present, the gaseous components of higher molecular weight at temperatures of the order of 300° C., maintaining said contact for not more than the duration of the activity of the wire resulting from said 700° C. heating while gradually raising the wire to a temperature less than that necessary without the aforesaid preliminary treatment for detecting the lower molecular weight components, continuously ascertaining the wire temperature, and noting the increase in temperature above the calibrated temperature at any time during said temperature raising to indicate the presence of catalytic combustion at that calibrated temperature indicative of the presence of a known component of hydrocarbon gases.
